UNITED STATES PATENT OFFICE.

WASHINGTON JONES, OF LANCASTER, PENNSYLVANIA, ASSIGNOR TO
CHARLES A. INGLIS, OF SAME PLACE.

TOBACCO-BOOKING MACHINE.

SPECIFICATION forming part of Letters Patent No. 339,662, dated April 13, 1886.

Application filed December 16, 1882. Serial No. 79,442. (No model.)

To all whom it may concern:

Be it known that I, WASHINGTON JONES, a citizen of the United States, residing at Lancaster, in the county of Lancaster and State of Pennsylvania, have invented certain Improvements in Tobacco-Booking Machines, of which the following is a specification.

My invention relates to machines for stretching the leaves of tobacco to be used for wrapping cigars; and the objects of my improvements are to stretch the whole leaf thoroughly and in such manner as to save the ends of the leaf, and to stretch it better and more quickly than is at present done. I attain these objects by the mechanism illustrated in the accompanying drawings, in which—

Figure I is a view in front perspective, and Fig. II an elevation of the rear of the booker, (the side on which the operator sits.)

The booking-block A is circular on the top and supported by legs n. Levers b are hinged to the bottom of the block A on each side at h, and their lower ends are connected by a spring, S, which serves to force the lower ends of the levers apart and cause the upper ends thereof to press against the block. There is a hook, m, fastened into the outer faces of the tops of the levers b, which, by means of the connecting-rods d and treadles T, enables the tops of the levers b to be pulled or drawn away from the booking-block A. Between the tops of the levers b and the sides of the block A are placed shifting-blocks e, which can be moved up or down by means of clamps e, working through slots r in the levers b. Across the top of the booking-block is placed a wisp or mat, K, of some flexible texture, folded as may be desirable. This I prefer laying loosely across the block, so that its ends are caught by the levers, although it may be fastened immediately to the block.

In using my device it is placed between the knees, the inner corners of the block A being cut out, as shown at x, so as not to interfere with the legs of the operator, that the treadle 45 may be comfortably worked by the feet. In booking the tobacco the upper end of one of the levers b is opened, the end of a leaf is smoothed down on the block and caught by the lever as it is allowed to close. The leaf is then 50 stretched over the top of the block and passed under the other lever, which closes upon it. It is desirable for the sake of economy to hold the leaves at the ends, for which purpose I use the shifting block e to conform to the va- 55 rious lengths of the leaves. The mat K, raising a ridge across the booking-block, greatly facilitates the opening and spreading of the leaf.

The parts of the machine brought into contact with the tobacco are covered with canvas or other similar material; but if it is necessary for preserving moisture in the tobacco, they can be covered with rubber, sponge, or the like. 60

What I claim as my invention, and desire to secure by Letters Patent, is—

1. The combination, with the booking-block A, of the levers b, hinged at the points h, the spring S, the hooks or arms m, the connect- 70 ing-rods d, and the treadles T, all substantially as and for the purpose specified.

2. The combination, with a booking-block, of levers hinged to the sides, treadles connect- 75 ed to the levers, and a spring for forcing the upper ends of the levers against the block, for the purpose specified.

WASHINGTON JONES.
